UNITED STATES PATENT OFFICE

GUSTAF DAVID SUNDSTRAND, OF ROCKFORD, ILLINOIS, ASSIGNOR TO SUNDSTRAND MACHINE TOOL CO., OF ROCKFORD, ILLINOIS, A CORPORATION OF ILLINOIS

PUMP

Application filed March 22, 1928. Serial No. 263,656.

This invention relates generally to pumps and more particularly to a variable output displacement pump.

It is a general object of the invention to provide a new and improved positive displacement pump.

It is another object of the invention to provide an improved variable displacement hydraulic pump.

10 It is another object of the invention to provide a multiple cylinder high pressure pump embodying means to supply fluid to the cylinders at a comparatively low pressure.

15 Another object is to provide a multiple cylinder positive displacement pump embodying novel means for varying the output of the pump.

20 A further object is to provide a new and improved multiple cylinder positive displacement pump embodying levers for actuating the pistons, and having an adjustable connection therewith to permit of varying of the stroke of the pistons.

In pursuance of the foregoing objects, I 25 aim to provide a pump comprising a plurality of cylinders having pistons reciprocating therein, means to reciprocate said pistons adjustable to vary the stroke of the pistons, a gear pump arranged to supply fluid to the 30 cylinders at low pressure, and a valve device arranged to control the inlet of low pressure fluid and outlet of high pressure fluid to and from the cylinders.

35 Further objects and advantages of the invention will become apparent as the description proceeds.

In the drawings:

Fig. 1 is a vertical section through the preferred form of the invention taken substantially along the line 1—1 of Fig. 3.

Fig. 1^a is a view of the valve member.

Figs. 1^b to 1^f inclusive are transverse sections along the lines b—b to f—f respectively of Fig. 1^a.

45 Fig. 2 is a view of the left hand end of the pump shown in Fig. 1, with the mounting plate removed, the view being taken on the line 2—2 of Fig. 1.

50 Fig. 3 is a section along the line 3—3 of Fig. 1.

While my invention is susceptible of embodiment in many different forms, I have shown in the drawings and will herein describe in detail one such embodiment, with the understanding that the present disclosure is 55 to be considered as an exemplification of the principles of the invention and is not intended to limit the invention to the embodiment illustrated. The scope of the invention will be pointed out in the appended claims.

As illustrated herein, the invention in its exemplary form comprises a housing 1 having a side wall 2 somewhat irregular in shape (see Fig. 3) and end walls 3 and 4. The means for actuating the pump is shown in the form 60 of a drive shaft 5 rotatably mounted in the upper portion of the housing by means of a pair of ball bearings 6, 7, one end of the shaft extending through an aperture in the wall 3 for connection to a prime mover. Mounted 65 on this shaft for rotation therewith are a plurality of angularly displaced eccentrics which, as described hereinafter, are arranged to actuate a plurality of pistons 9.

The pistons are preferably mounted in a 70 unitary cylinder block 10 having bores 11, for receiving the pistons, and which is pivotally mounted on an axis beneath and extending parallel to the axis of the shaft 5. As illustrated herein, the cylinder block has bearing portions 12, 13 at its opposite ends rotatably mounted in bearing portions 14, 15 formed in the end walls of the housing 1.

The pistons 9 are preferably rounded on 75 their upper ends and arranged to be actuated by a plurality of arms or levers 16 which are herein shown as being independently fulcrumed at one end on a common shaft 17 which extends parallel to the shaft 5. The free ends of the levers are arranged to be actuated by the eccentrics 8 and are provided with rollers 18 which ride upon the eccentrics. As will be most readily apparent from Figs. 1 and 3, when the shaft 5 is rotated, the force arms of the levers, i. e. the portions of 80 the levers between the fulcrums thereof and the connection with the eccentrics, will be actuated successively by means of the eccentrics, the load arms of the levers in turn forcing the pistons downwardly. As disclosed 85 90 95 100

herein, the pistons are arranged to be forced upwardly on their return strokes by means of pressure fluid as hereinafter more fully described.

5 The invention contemplates varying the stroke of the pistons by adjusting the effective length of one arm of the levers. For this reason the levers illustrated herein are preferably arcuate in form on a radius equal 10 to the distance between the pivotal axis of the cylinder block 10 and the center of the fulcrum shaft 17. Thus in the exemplary form of the invention the load arms of the levers may be varied by moving the cylinder block 15 about its pivotal axis from the position shown in Fig. 3 to a position wherein the pistons would contact the arms along the axis of the shaft 17, and the stroke of the pistons correspondingly varied from the maximum as determined by the throw of the eccentrics to a 20 minimum, (in this case zero).

To permit of so varying the stroke of the pistons means is provided for rocking the cylinder block 10 about its pivotal axis. Preferably a segmental gear 19 is secured to one 25 end of the cylinder block, which gear meshes with a pinion 19^a mounted on one end of a control shaft 20. This shaft extends through a bore in the end wall 4 of the housing and 30 also through a mounting plate 21, to receive a hand lever 22 (shown in part). By rotating the shaft 20 by means of the hand lever, the cylinder block 10 may be rocked on its pivotal axis and the output of the pump varied as 35 hereinafter more fully described.

In order to insure a definite amount of 40 fluid entering each cylinder during each return stroke of the pistons, the invention contemplates means for supplying fluid to the cylinders under pressure, the pressure being sufficient to force the pistons upwardly into 45 constant engagement with the arms 16 on their return stroke as well as to retain the rollers 18 in constant contact with the eccentrics so as to obviate the necessity of using 50 springs or a positive connection between the arms and the pistons. As illustrated herein, a gear pump comprising intermeshing gears 23, 24 is provided for supplying the fluid under 55 pressure to the cylinders. These gears are positioned intermediate the outer surface of the housing wall 3 and a plate 25 which is spaced therefrom by means of a collar 26 and secured thereto by a plurality of 60 bolts 27. The gear 23 is rotatably mounted on a pin 28 supported by the end wall 3 and is arranged to be driven by means of a gear 29 keyed to the drive shaft 5. The gear 24 is shown mounted on one end of a cylindrical 65 valve member 30 which member is rotatably mounted in a valve sleeve 31. The sleeve is preferably positioned concentrically with the pivotal axis of the cylinder block 10 and in a bore 32 therein, and is secured against rotation by means of a pin 33 extending through

the sleeve and an apertured plug 34 secured to the housing.

The sleeve 31 is provided with a plurality of ports 35 therein, one for each cylinder, which ports are preferably positioned adjacent the left hand walls of the cylinders as shown in Fig. 3, so that when the cylinder block is rocked in a counter-clockwise direction, the ports remain in communication with the cylinders. 70

75 The valve member 30 is arranged to control the inlet of low pressure fluid to the cylinders during the intake strokes of the pistons and to control the outlet of high pressure fluid from the cylinders during the exhaust strokes of the pistons and is therefore provided with a longitudinal low pressure intake passage 36 connecting with a plurality of low pressure intake ports 37 and has high pressure exhaust ports 38 which connect with an axially extending high pressure exhaust passage 39. This exhaust passage connects with a passage 40 in the plug 34 which serves as an outlet connection for the pump. The intake ports 37 and exhaust ports 38 are 80 spaced about the periphery of the valve member so that during continuous rotation of the valve member during the operation of the pump, the ports are properly timed with the reciprocations of the pistons as determined by 85 the eccentrics, first to admit low pressure fluid to return the pistons and thereby completely fill the cylinders, then to cut off communication between the low pressure supply and the cylinders and open the high pressure 90 exhaust passages. 100

The inlet and outlet to the pump are preferably provided at opposite ends of the housing. Thus as illustrated herein the inlet is provided adjacent the gear pump by means of a port 41 in the end plate 25, this port being in communication with a passage 42 which connects with an intake chamber 43 of the gear pump. From the exhaust chamber 44 of the gear pump, a passage 45 connects with an annular port 46 which surrounds one end of the valve member 30 and establishes constant communication with the intake passage 36 in the valve member. The invention contemplates that the gear pump will provide fluid in quantities greater than the output of the high pressure end of the pump and that a suitable by pass will be provided for the excess fluid. This will insure that the cylinders will at all times be completely filled with fluid during the intake strokes of the pistons. 110

115 In operation, the fluid admitted through the port 41 passes through the gear pump, which creates a pressure of approximately 30 pounds per square inch, and from the exhaust chamber 44 of the gear pump the fluid passes through the connecting passages 45, port 46, passage 36, and ports 37 and 35 to the cylinders during the intake strokes of the pistons, any excess fluid from the gear pump 120 130

being returned to the supply through a suitable by pass (not shown). During the exhaust strokes of the pistons the fluid will be forced out through the ports 35 and 38 and the exhaust passages 39 and 40. Figs. 1^a to 1^c inclusive illustrate the valve member in detail and show the proper timing of the intake and exhaust ports for the preferred form of the invention as disclosed herein.

From the foregoing it will be apparent that I have provided a pump of positive displacement such for example as is adapted for use in connection with supplying hydraulic fluid for moving tool or work carriers in machine tools wherein it is desired to move the carrier at a uniform rate of speed irrespective of fluctuations in load on the carrier. When using an incompressible fluid such results can readily be obtained. It will also be seen that I have provided means for varying the output of the pump from zero to a maximum determined by the capacity of the pump, this means being arranged to permit of an infinite number of steps intermediate maximum and minimum. Thus when so used in connection with the feeding of a tool or work support, the rate of such feed may be readily varied.

I claim as my invention:

1. A pump comprising, in combination, a housing, a drive shaft rotatably mounted in said housing, a plurality of angularly displaced eccentrics on said shaft, a plurality of pivotally fulcrumed levers engaging said eccentrics, a cylinder block pivotally mounted on an axis parallel to said shaft, said cylinder block having inlet and outlet means, and a plurality of pistons mounted in said block arranged to be actuated by said arms to discharge liquid through said outlet means.

2. In a pump comprising a cylinder block having a plurality of pistons slidably mounted in cylinders, means for controlling the flow of a fluid to and from said cylinders, and means for reciprocating said pistons including a drive shaft, a plurality of angularly displaced eccentrics on said shaft, and means actuated by and in continuous contact with said eccentrics having adjustable connections with said pistons to permit the stroke of the pistons to be varied.

3. A pump comprising, in combination, a housing, a drive shaft rotatably mounted in said housing, a plurality of eccentrics on said shaft, a plurality of arcuately formed levers fulcrumed on an axis parallel to said shaft and having rollers on their free ends engageable by the eccentrics, a block having cylinders therein pivotally mounted on an axis parallel to said shaft having inlet and discharge ports formed therein for said cylinders, and a plurality of pistons slidably mounted in said block and arranged to be actuated by said levers.

4. A pump comprising, in combination, a

rotatably mounted shaft, a plurality of angularly displaced eccentrics on said shaft, a plurality of arcuately formed levers fulcrumed on an axis parallel to said shaft and having their force arms engageable by said eccentrics, a cylinder block, having inlet and discharge ports formed therein for the cylinders, a plurality of pistons slidably mounted in said block arranged to be actuated by the load arms of said levers and means arranged to adjust the effective length of one set of said arms whereby to vary the stroke of the pistons.

5. A pump having, in combination, a rotatably mounted shaft, a cylinder having inlet and discharge ports, a reciprocatory piston mounted in said cylinder, a pivotally fulcrumed lever having a load arm of adjustable length and a force arm of constant length arranged to actuate said piston, means carried on said shaft arranged to operate the force arm of the lever and means to adjust the effective length of the load arm of said lever whereby to vary the piston stroke.

6. In a pump embodying a cylinder having intake and discharge ports and a piston in said cylinder arranged to deliver high pressure fluid at a predetermined volume per stroke, the combination, of a gear pump arranged to deliver fluid at a comparatively low pressure to said piston and a valve driven through said gear pump for controlling the inlet of low pressure fluid and the exhaust of high pressure fluid to and from said piston.

7. A pump comprising, in combination, a pivotally mounted cylinder, means providing intake and discharge ports for said cylinder, a piston in said cylinder, an arm pivotally mounted on an axis parallel to the cylinder pivot and arranged to actuate said piston, and means for oscillating said arm, pivotal movement of said cylinder being arranged to vary the stroke of the piston.

8. A pump comprising, in combination, a cylinder, a piston in the cylinder, means for supplying fluid under pressure to the cylinder comprising a gear pump and a control valve, said valve and one gear of said pump being mounted on the same shaft, and means to actuate the piston in the opposite direction.

9. A pump comprising, in combination, a pivotally mounted cylinder block having inlet and discharge ports, a plurality of pistons reciprocably mounted in the cylinders of said block, a plurality of independent pivotally mounted levers operating on said pistons, said levers being arcuate in form, and means to pivot said cylinder block to vary the stroke of the pistons.

10. A pump comprising, in combination, a housing, a block having a plurality of cylinders therein mounted in said housing, said block having inlet and outlet openings for said cylinders, pistons in said cylinders,

a rotary valve for controlling said inlet and outlet openings, a gear pump for supplying liquid under low pressure to said valve, said gear pump having one of its gears mounted on and rotatable with said valve and the other one of its gears rotatably mounted in said housing, a shaft mounted in said housing, means operable by rotation of said shaft to actuate said pistons, and a pinion on said shaft in driving engagement with one of the gears of said pump so that said pump and said valve are operated by said shaft.

11. A pump comprising, in combination, a housing, a cylinder block having cylinders formed therein and mounted in said housing for pivotal movement about an axis perpendicular to said cylinders, said block having inlet and discharge ports for said cylinders, pistons in said cylinders, a plurality of arcuately formed levers pivoted at one end in said housing and each lever engaging one of said pistons, a shaft mounted in said housing having means engaging said levers to rock the same about their pivots, said cylinder block being tilttable about its pivotal axis to engage said pistons with different points on said levers whereby to vary the stroke of the pistons, a valve for controlling said ports mounted in said block for rotation about the pivotal axis thereof, a gear pump having one gear mounted in the wall of said housing, and the other gear mounted on said valve for rotation therewith, one of said gears being driven from said shaft.

12. In a pump, in combination, a pivotally mounted block having a cylinder therein, a piston in said cylinder, means to conduct fluid to and from the cylinder, and means for actuating said piston comprising a pivotally mounted lever arcuate in form throughout a substantial portion of its length and arranged to engage the outer end of the piston, means for adjusting the cylinder block about its pivot for varying the point of operative engagement of said piston with said lever and means for oscillating said lever.

In testimony whereof, I have hereunto affixed my signature.

GUSTAF DAVID SUNDSTRAND.
